Primary Examiner — Keli L Hill

(57) **CLAIM**

The ornamental design for a bottle, as shown and described.

DESCRIPTION

1.-4. Bottle

1.1 is a front elevation view.

1.2 is a rear elevation view.

1.3 is a side elevation view.

1.4 is a opposite side elevation view.

1.5 is a top plan view.

1.6 is a bottom plan view.

1.7 is a top perspective view.

1.8 is an alternate front elevation view shown with the cap removed.

1.9 is an alternate top perspective view shown with the cap removed.

2.1 is a front elevation view.

2.2 is a rear elevation view.

2.3 is a side elevation view.

2.4 is a opposite side elevation view.

2.5 is a top plan view.

2.6 is a bottom plan view.

2.7 is a top perspective view.

2.8 is an alternate front elevation view shown with the cap removed.

3.1 is a front elevation view.

3.2 is a rear elevation view.

3.3 is a side elevation view.

3.4 is a opposite side elevation view.

3.5 is a top plan view.

3.6 is a bottom plan view.

3.7 is a top perspective view.

3.8 is an alternate front elevation view shown with the cap removed.

4.1 is a front elevation view.

4.2 is a rear elevation view.

4.3 is a side elevation view.

4.4 is a opposite side elevation view.

4.5 is a top plan view.

4.6 is a bottom plan view.

4.7 is a top perspective view.

4.8 is an alternate front elevation view shown with the cap removed.

Each design is for a bottle with a removable closure cap, e.g. for containing and dispensing a liquid product.
